UNITED STATES PATENT OFFICE.

JAMES CORBETT AKINS, OF BECKVILLE, TEXAS, ASSIGNOR OF ONE-HALF TO AUGUSTUS P. ROBERTS, OF BECKVILLE, TEXAS.

COMBINED CUT-OUT VALVE, PRIMING DEVICE, AND AUXILIARY AIR INLET FOR INTERNAL-COMBUSTION ENGINES.

Application filed March 29, 1922. Serial No. 547,808.

To all whom it may concern:

Be it known that I, JAMES C. AKINS, a citizen of the United States, residing at Beckville, in the county of Panola and State of Texas, have invented certain new and useful Improvements in Combined Cut-Out Valves, Priming Devices, and Auxiliary Air Inlets for Internal-Combustion Engines, of which the following is a specification, reference being had to the accompanying drawings.

This invention relates to improvements in a combined cut-out valve priming device and auxiliary air inlet for internal combustion engines.

An important object of the invention is to provide a device which may be separately employed for accomplishing the above objects and which consists in a simple mechanism disposed intermediate the intake manifold of the engine and the cut-out valve of the exhaust.

A further object of the invention is to provide a device of this character which is extremely simple in construction and operation, efficient and durable in service and a general improvement in the art.

These and other objects I attain by the construction and arrangement shown in the accompanying drawings wherein for the purpose of illustration is shown a preferred embodiment of my invention and wherein like reference characters designate like parts throughout.

In the drawings:

Figure 1 is a diagrammatic view showing an apparatus constructed in accordance with my invention applied to an internal combustion engine;

Figure 2 is a side elevation of the control valve;

Figure 3 is a section on the line 3—3 of Figure 1;

Figure 4 is a vertical section taken through the cut-out valve operating cylinder;

Figure 5 is a section taken through the cut-out; and

Figures 6, 7, 8 and 9 are sectional views showing various positions of the valve to give the various connections desired.

Referring now more particularly to the drawings, the numeral 10 indicates an en-

gine, 11 the intake manifold thereof, 12 the exhaust manifold and 13 the exhaust conduit connecting the exhaust manifold with the muffler 14. The numeral 15 indicates a cut-out valve disposed intermediate the muffler and exhaust manifold and of the usual construction. These valves, 60 as is well known to those familiar with the art, embody a flap valve 16 movable to close an opening 17 or to close the exhaust passage of the conduit 13 and direct the gases thereof through the opening 17 into the open 65 air. These valves are provided upon the stem 18 thereof with an operating lever 19 and the valve is held in closed position by means of a spring 20.

In accordance with my invention I provide a cylinder 21 having shiftable therein a piston 22, the rod 23 of which is connected, as by a link 24, with the operating lever 19 of the cut-out valve. The piston of the cylinder is so arranged that the piston is at one end of the cylinder when the cut-out valve is in its closed position.

The numeral 26 designates a control element in the present instance disclosed as a three way valve having one port thereof connected by a conduit 27 with the intake manifold, a second port connected by a conduit 28 with the end of the cylinder 21 remote from that at which the piston 22 is disposed when the cut-out valve is closed, 85 and the third port of which is connected with a priming cup 29. It will be seen that when the valve body 30 is so arranged that

the main port 31 thereof connects the conduits 27 and 28 the suction within the intake manifold 11 will create a vacuum within the cylinder 21 causing the piston to be drawn upwardly and by reason of its connection with the arm 19, to open the cut-out valve against the action of the spring 95 20. If the valve is now rotated so as to connect the branch port 32 thereof with the outlet at which the conduit 28 is connected, the main port 31 will be in connection with the priming cup outlet and air will be admitted to the conduit 28 permitting the piston to return to its normal position under the action of the spring 20. If the valve is positioned so as to connect the priming cup with the intake manifold it will be seen that 100 the priming cup may be employed either

for the admission of fuel to assist in starting the engine or for the admission of air during operation of the engine to alter the ratio of the combustible mixture admitted 5 to the cylinder. The control member 26 may be arranged at any desired point, preferably upon the dash D of the vehicle where it will be readily accessible to the operator.

While I have in the present showing 10 closed a three way valve for accomplishing the connections desired, it will be understood that I do not wish to be limited to such specific structure, for this construction may be altered in many ways without in 15 any manner departing from the spirit of my invention, nor do I wish to be understood as limiting myself to the specific arrangement hereinbefore set forth, as the same is likewise capable of many changes 20 and I accordingly do not limit myself there- to except as hereinafter claimed.

I claim:

1. The combination with an internal combustion engine embodying the usual intake 25 manifold, exhaust manifold, and muffler connected to the exhaust manifold to receive the exhaust gases therefrom, of a cut-out valve arranged intermediate the muffler and exhaust manifold, a cylinder, a piston 30 reciprocable within the cylinder, a connection between the piston and the cut-out valve whereby the cut-out valve is operated upon reciprocation of the piston, and a connection 35 between one end of the cylinder and the intake manifold of the engine.

2. The combination with an internal combustion engine embodying the usual intake manifold, exhaust manifold, and muffler connected to the exhaust manifold to receive 40 the exhaust gases therefrom, of a cut-out valve arranged intermediate the muffler and exhaust manifold, a cylinder, a piston reciprocable within the cylinder, a connection 45 between the piston and the cut-out valve whereby the cut-out valve is operated upon reciprocation of the piston, and means for connecting one end of said cylinder with the intake manifold of the engine or with 50 the atmosphere.

50 3. The combination with an internal combustion engine embodying the usual intake manifold, exhaust manifold, and muffler connected to the exhaust manifold to receive the exhaust gases therefrom, of a cut-out 55 valve arranged intermediate the muffler and exhaust manifold, a cylinder, a piston reciprocable within the cylinder, a connection between the piston and the cut-out valve whereby the cut-out valve is operated upon 60 reciprocation of the piston, and identical means for connecting one end of said cylinder with the intake manifold of the engine, or with the atmosphere and for connecting the intake manifold with the atmos- 65 phere.

4. The combination with an internal combustion engine embodying the usual intake manifold, exhaust manifold, and muffler connected to the exhaust manifold to receive the exhaust gases therefrom, of a cut-out 70 valve arranged intermediate the muffler and exhaust manifold, a cylinder, a piston reciprocable within the cylinder, a connection between the piston and the cut-out valve whereby the cut-out valve is operated upon 75 reciprocation of the piston, and identical means for connecting one end of said cylinder with the intake manifold of the engine or with the atmosphere and for connecting the intake manifold with the atmosphere 80 embodying a priming valve.

5. In combination with an engine embodying an intake manifold, an exhaust manifold and exhaust pipe leading from the manifold, a spring closed cut-out valve disposed in the exhaust pipe and embodying an operating arm, a cylinder, a piston reciprocable within the cylinder and normally disposed in one end thereof, an operative connection between the piston and operating 90 arm of the cut-out valve and a controllable connection between the opposite end of the cylinder from that in which the piston is normally disposed and the intake manifold of the engine. 95

6. In combination with an engine embodying an intake manifold, an exhaust manifold, exhaust pipe leading from the manifold, a cut-out valve disposed in the exhaust pipe movable to open and closed positions 100 and normally held in closed position, vacuum operated means for moving the cut-out valve to the open position, and means for connecting said vacuum operated means to the intake manifold of the engine. 105

7. In combination with an engine embodying an intake manifold, an exhaust manifold, exhaust pipe leading from the manifold, a cut-out valve disposed in the exhaust pipe movable to open and closed positions 110 and normally held in closed position, vacuum operated means for moving the cut-out valve to the open position, means for connecting said vacuum operated means to the intake manifold of the engine including a 115 vacuum cylinder, a three way valve, a connection between one port of the three way valve and the vacuum cylinder, a connection between the second port of the three way valve and the intake manifold, and a 120 connection between the third port of the three way valve and the atmosphere.

8. In combination with an engine embodying an intake manifold, an exhaust manifold, exhaust pipe leading from the manifold, a cut-out valve disposed in the exhaust pipe movable to open and closed positions 125 and normally held in closed position, vacuum operated means for moving the cut-out valve to the open position, means for connecting 130

said vacuum operated means to the intake manifold of the engine including a vacuum cylinder, a three way valve, a connection between one port of the three way valve and the vacuum cylinder, a connection between the second port of the three way valve and the intake manifold, and a connection be-

tween the third port of the three way valve and the atmosphere including a priming cup.

In testimony whereof I hereunto affix my signature.

10

JAMES CORBETT AKINS.
